MANUALLY USABLE CORN CUTTER
Irene Trenor, 210 W. 12th St., Streator, Ill.
Filed Jan. 24, 1961, Ser. No. 84,638
2 Claims. (Cl. 146—4)

This invention relates to a device through the medium of which kernels of corn, either hot or cold, may be properly and nicely cut and stripped from the cob, and has to do with a specially devised structural adaptation having featured improvements which achieve the desired ends in a simplified and practical manner.

Briefly, the invention embodies a base and a complementary manually usable implement. The base comprises a simple disk-like plate having a centralized upstanding cob impaling and anchoring prong. The implement comprises a vertically elongated split sleeve provided with handles and an improved cutting edge.

In carrying out a preferred embodiment of the invention an elongated longitudinally split downwardly tapering sleeve is employed. This sleeve when being used sheathes or envelopes the cob and kernels thereon and is forced vertically and downwardly by way of a pair of diametrically opposite handles or handgrips.

The sleeve is of prerequisite length relative to the length of what may be considered an average ear of corn and it is constructed of non-corrodible sheet material, is open at upper and lower ends, is resilient and expansible and contractible to achieve clean cleavage of the kernels of corn, said sleeve expanding and contracting as conditions require to accomplish highly satisfactory and efficient results.

The handgrips are novel in that they have upper horizontal end portions which are directed inwardly toward each other and which radiate from the upper edge of the sleeve, the adjacent inner ends being riveted to the sleeve. These handgrips are of prescribed length and shape for comfort and convenience and the lower ends are securely fastened to median diametrically opposite portions of the sleeve with a view toward thrusting the sleeve downwardly with reliability and making it possible to do the desired cutting and stripping result. In fact, the result can ordinarily be accomplished by way of a single continuous downward stroke.

In addition, the lower or leading ends of the overlapped portions of the split sleeve at the tapered bottom of the sleeve are arcuately curved and diverge outwardly and downwardly and merge into and meet with the main cutting edge, said main cutting edge being substantially straight and disposed in a plane at right angles to the length wise axis of the sleeve.

The invention also contemplates the use of a base comprising a simple disk-like flat-faced plate having a central upstanding impaling and anchoring prong which penetrates the ear of corn, that is the butt end, thus securely holding the ear in a vertical ready-for-use position.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is an exploded perspective view showing the complete device; namely, the base, and the manually usable cutter implement and further showing the ear of corn ready to be stripped of its kernels;

FIG. 2 is a view on a slightly larger scale which may be said to be a front elevation;

FIG. 3 is a section of a fragmentary nature taken on the vertical line 3—3 of FIG. 2; and

FIG. 4 is a top plan view of the implement seen for example in FIG. 2.

2

With reference to FIG. 1 the base is denoted by the numeral 6 and comprises a disk or plate of suitable diameter and material having a flat bottom 8 to rest on a table or other stationary support and having a substantially flat top 10 to accommodate the butt or large end 12 of the ear of corn 14. The impaling or anchoring prong 16 is joined with and rises from the central portion of the disk and is embedded in the cob to hold the ear of corn in a vertical ready-to-function position.

10 The manually usable cutting implement is denoted as an entity by the numeral 18 and comprises an imperforate vertically elongated truncated conical sleeve. That is to say the sleeve is in the form of a downwardly tapering cone and is open at upper and lower ends. The upper end is denoted at 20. The lower end is denoted at 22 and this end is sharpened to provide a cutting edge 24 which may be described as in a plane at right angles to the longitudinal axis of the over-all sleeve. The sleeve is longitudinally split and is made of resilient metal or equivalent material and the lengthwise edge portions 26 and 28 overlap each other and obviously permit the sleeve to expand and contract depending on the cross sectional size of the ear of corn which is to be acted on. It will be noted particularly in FIGS. 2 and 3 that the lower end 20 portions of the overlapping portions 26 and 28 have curved or arcuately formed auxiliary cutting edges 30 and 32. These edges may be said to diverge outwardly and downwardly and to in this manner form an inverted V-shaped leading end portion. Conversely the edges 30 and 32 may be said to join at their lower ends with the main cutting edge 24 from which points they curve upwardly and converge to form an expansible and contractible crotch 34.

25 The handles or handgrips are identical in construction and are mounted on the expansible and contractable sleeve at diametrically opposite points each handgrip being denoted by the numeral 36. The handgrips have longitudinally bowed main portions 38 the lower ends 40 of which are bent laterally and riveted or otherwise secured in place at 42. These points of attachment 42 may be described as not only diametrically opposite each other but intermediate the upper and lower ends of the sleeve considered as an entity. The upper inwardly directed end portions of the handgrips are horizontally disposed as at 44 and the free ends are bent down as at 46 in FIG. 1 where they are riveted or otherwise secured in place at 48. This arrangement of a pair of handgrips at diametrically opposite points with the handgrips shaped and mounted as shown provides reliable handling means

wardly over the corn ear, said sleeve being circular in cross-section from end to end, being split longitudinally and made of resilient sheet material, the lengthwise end portions of said sleeve coincident with the split part of the sleeve being overlapped and slidably contacting each other, said sleeve being radially expansible and contractible and tapering from the upper trailing end toward the lower leading end, the lower leading end of said sleeve having a main cutting edge and cooperating associated auxiliary cutting edges, said main cutting edge being disposed in a plane at right angles to the longitudinal axis of the sleeve, said auxiliary cutting edges merging into and being joined at lower leading ends with the coacting adjacent end portions of said main cutting edge and curving and converging upwardly from the plane of said main cutting edge and merging with the respective marginal edges of the lower end portions of said overlapped sleeve portions and providing an inverted V-shaped expansible and contractible crotch, and, in combination, a pair of hand-grips attached to diametrically opposite sur-

faces of said sleeve and individually positioned on the sleeve lengthwise thereof and at an approximate 90° from and relative to the vertex of said crotch.

2. The structure defined in claim 1 and wherein said grips have coplanar lateral upper ends projecting radially outward in a plane from the upper end of said sleeve and have lower ends affixed to portions of the sleeve intermediate the upper and lower ends of the sleeve to facilitate handling and controlling the expansible and contractible movements of the overlapped portions and the descending cleaving action of said main and auxiliary cutting edges.
